(57) **CLAIM**

The ornamental design for a boot, as shown and described.

DESCRIPTION

FIG. 1 is a front right-side perspective view of a first embodiment of a boot showing our new design;

FIG. 2 is a front view thereof;

FIG. 3 is a rear view thereof;

FIG. 4 is a right-side view thereof;

FIG. 5 is a left-side view thereof;

FIG. 6 is an enlarged top view thereof; and,

FIG. 7 is an enlarged bottom view thereof.

FIGS. 1-7 depict a first embodiment for a right foot boot; a second embodiment for a left boot, which is a mirror image of the preceding embodiment, is also claimed but not shown. The broken lines appearing in FIGS. 1-7 show portions of the boot that form no part of the claimed design.

The consistent length broken lines appearing in FIGS. 1-7 show portions of the Boot that form no part of the claimed design.

In the FIG. 6 view, the dot-dash broken line interior perimeter boundary line and grayed interior of the boot within it form no part of the claimed design.
